ABSTRACT

These dyeing compositions containing precursors of oxidizing dyestuffs, alkalinizing agents and a weak oxidizing agent added before using the compositions, contain as an alkalinizing agent the carbonate of an amino acid alkali metal or ammonium salt, as an at least partial substitute for ammonia previously used as an alkalinizing agent, possibly in conjunction with organic bases, said carbonate being neither volatile nor aggressive and making it possible to obtain dyeing compositions free of unpleasant odors and free of any aggressiveness for the scalp while yielding particularly attractive and aesthetic shades.

9 Claims, No Drawings

**KERATINIC FIBRES OXIDATION DYEING
COMPOSITIONS CONTAINING A CABONATE OF
AN ALKALI METAL AMINO ACID**

This is a continuation of application Ser. No. 5 204,379, filed Dec. 2, 1971, now abandoned.

FIELD OF THE INVENTION

The present invention relates to novel dyeing compositions for dyeing keratinic fibres, notably human hair, which are free of the inconveniences characterizing conventional dyeing compositions.

BACKGROUND OF THE INVENTION

To dye keratinic fibres and more particularly human hair, chemical intermediates hereinafter referred to as "Precursors of oxidation dyestuffs" are usually employed and these intermediates, through an oxidation process consisting in utilizing a low oxidizing agent in an alkaline medium, lead to the formation of pigments distributed through the keratinic fibre to yield variegated hues depending on the nature and proportions of said precursors used in admixture and of which the total percentage in the dyeing composition, not including the oxidizer added just before the actual use, varies as a rule from about 0.2 to about 15% by weight.

The main precursors of oxidation dyestuffs generally employed consist essentially of aromatic diamines, such as p-phenylene diamine, p-toluylene diamine, m-toluylene diamine, and their substituted derivatives such as nitro p-phenylene diamine; the amino-phenols and their derivatives such as 2,4-diamine anisol sulfate and p-N-methylamino phenol sulfate; diphenols such as resorcinol and hydroquinone; etc..

The most widely used weak oxidizing agents are hydrogen peroxide in aqueous solution ranging as a rule from 3 to 10% H_2O_2 by weight, urea peroxide, and sodium perborate.

The alkaline medium is obtained by adding ammonia to the above-listed precursors for the triple purpose of preparing the hair to a maximum receptivity by swelling it and facilitating the penetration of the other components of the dyeing composition, creating favorable pH conditions for performing the oxidation and making the oxygenated water unstable.

The presence of ammonia in the dyeing composition, in amounts as high at 12 to 15% by weight and in the form of an aqueous solution at 22° Baume is a constant source of inconveniences and discomfort both for the user and for the person to which the product is applied. In fact, the suffocating odor of ammonia appears unavoidably when the other component elements of the dyeing composition are mixed up with the oxidizer just before the actual use, then during the application of the product and even during the time necessary for allowing this product to exert its activity.

On the other hand, when treating relatively sensitive scalps, ammonia produces in all cases reactions ranging from slight pricking to the impression of intense burns. This last effect is almost automatic whenever a dyeing operation is performed after a bleaching operation having already rendered the scalp more sensitive.

These inconveniences are extremely noxious and make the application rather unpleasant.

Moreover, since ammonia tends to become diffused through a great number of plastic materials and elastomers, these substances cannot be used for containing

and storing known dyeing compositions for keratinic fibres, irrespective of the method employed. More particularly, it is not possible to pack these dyeing compositions in aerosol containers of any type known per se which comprise twin valves and twin compartments, i.e. one compartment consisting of a flexible bag or bladder or plastic or elastomeric material, enclosed in the other compartment, generally of suitable metal, which may advantageously contain the oxidizing agent for these compositions, which is adapted to be mixed up with the actual composition when using the product; in fact, it is well known that the ammonia diffused through the walls of said bag or bladder would decompose the oxygen peroxide constituting the most usual oxidizing agent, so that large amounts of oxygen would be released and cause the internal pressure of the container to rise rapidly until an explosion occurs while rendering the product gradually inefficient, in any case, due to the decomposition of the oxygenated water which had to be put in contact with the other components and was normally expected to become effective only at the actual time of use of the product, not before.

In order to obtain dyeing compositions free of any aggressiveness and adapted to be stored and packed in the manner set forth hereinabove, the Applicants provide novel formulae for products of the type disclosed hereinabove which are free, or contain only very small amounts of ammonia.

By eliminating or at least reducing to a substantial degree the ammonia content, the Applicants succeeded in developing products free of any unpleasant feelings as described hereinabove, of any problem concerning their application from the point of view of their aggressiveness with respect to the scalp. Another highly appreciable advantage of the products of this invention is that the aesthetic appearance of the hair treated therewith is better preserved and even enhanced. Whereas in the presence of ammonia the hair or other keratinic fibre has a rather lusterless and harsh appearance, as if it were dried up, when using ammonia-containing formulae, on the contrary, the fibre appears as brilliant and smooth, is disentangled much more easily, and has finally a much more attractive and aesthetic appearance.

SUMMARY OF THE INVENTION

Since the alkaline medium is definitely necessary for accomplishing the oxidation operation, the present invention provides dyeing compositions containing precursors of oxidation dyestuffs, alkalinizing agents, and a weak oxidizing agent to be added at the time of the actual application, said compositions being characterized in that they contain as an alkalinizing agent the carbonate of an amino acid alkali metal or ammonium salt, as an at least partial substitute for ammonia. Said carbonate is a non-volatile and non-aggressive alkaline agent.

Preferably, the amino acid consists of glycine or glycocoll, or amino-acetic acid, but it may also consist of lysine, methionine, tyrosine, glutamic acid, leucine, valine, alanine. These amino acids may be used in the racemic form or in the form of their optical isomers. The alkaline salt may be the sodium salt, the potassium salt or the lithium salt.

This carbonate of amino acid alkali metal or ammonium salt may be associated with organic bases such as

morpholine, monoethanolamine, diethanolamine, triethanolamine, etc.

The dyeing compositions according to this invention may be used in the form of aqueous solutions of gelling liquids (before use, converted into gels by the addition of the oxidizing agent) containing non-ionic or anionic surface-active products, and aqueous emulsions generally of cream consistency.

The proportion of the novel alkalinizing agent in these compounds is advantageously from 1 to 10% by weight and the proportion of the possible organic bases ranges preferably from 1 to 7% by weight, these proportions being calculated on the weight of the compound, not including the oxidizing agent.

By using the carbonate of an amino acid alkali metal or ammonium salt possibly associated with an organic base and free of ammonia as an alkalinizing agent, the Applicants observed that it was thus possible to obtain formulae giving very good results for dyeing applications made on hair having a color lighter than, or of same hue as, the desired shade, and on previously bleached hair. These are ideal application cases; the comfort of the person to whom the treatment is applied is complete; there are neither unpleasant odor nor any aggressiveness to the scalp; the shades thus obtained are extremely aesthetic; the hair is brilliant, smooth and easily disentangled. The advantages are identical with those obtained in the case of keratinic fibres in general.

DESCRIPTION OF THE PREFERRED EMBODIMENT

A few examples of dyeing compositions according to this invention which have been developed and formulated for these specific applications are given hereinafter.

In these examples, the term "balance to 1 kg" associated with "Demineralized water" means that sufficient water is added to produce 1 kg of the contemplated dyeing composition, and the abbreviation "q.s." applied to the precursors of oxidation dye-stuffs means "quantity sufficient for obtaining the desired shade." A mixture of precursors of oxidation dyestuffs suitable for obtaining a black shade (among other possible mixtures) is as follows:

p-toluylene diamine	20 g
2,4-diamino anisol sulfate	20 g
resorcinol	5 g

In these formulae the disodium salt of EDTA (ethylenediamine-tetracetic acid) is used as a sequestrant, sodium o-phenyl phenate as a bactericidal preserver, sodium bisulfite as a reducing agent for stabilizing the composition against oxidation during the storage, the quaternary ammonium compound as an agent for protecting or softening the hair (among suitable protection agents lauryl pyridinium chloride, cetyl trimethyl ammonium bromide, cetyl benzene dimethyl ammonium bromide, 1-hydroxyethyl 2-heptadecenyl imidazoline may also be cited); cetyl alcohol (self-emulsified by means of oxyethylated cetyl alcohol) as a base in an emulsion or cream for the compositions utilized in the form of emulsion or cream, oxyethylated nonyl phenol as a surface-active agent and propylene glycol as a dissolving intermediary for preventing the gelling before use in the case of composi-

tions utilized in the form of a gel formed by adding the oxidizing agent.

EXAMPLES 1 to 14: EMULSIONS OR CREAMS

Example 1.	Balance to	1 kg
Demineralized water	28 g	
Carbonate of sodium glycinate	2 g	
EDTA (disodium salt)	0.5 g	
Sodium o-phenyl phenate	10 g	
Sodium bisulfite at 36° Baume	160 g	
Self-emulsified cetyl alcohol	20 g	
Quaternary ammonium compound	2 g	
Perfume	q.s.	
Precursors of oxidation dyestuffs		
Example 2.	Balance to	1 kg
Demineralized water	28 g	
Carbonate of sodium glycinate	2 g	
EDTA (disodium salt)	0.5 g	
Sodium o-phenyl phenate	10 g	
Sodium bisulfite at 36° Baume	160 g	
Self-emulsified cetyl alcohol	20 g	
Quaternary ammonium compound	2 g	
Monooethanolamine	20 g	
Perfume	2 g	
Precursors of oxidation dyestuffs		
Example 3.	Balance to	1 kg
Demineralized water	28 g	
Carbonate of sodium glycinate	2 g	
EDTA (disodium salt)	0.5 g	
Sodium o-phenyl phenate	10 g	
Sodium bisulfite at 36° Baume	160 g	
Self-emulsified cetyl alcohol	20 g	
Quaternary ammonium compound	2 g	
Morpholine	30 g	
Triethanolamine	30 g	
Perfume	2 g	
Precursors of oxidation dyestuffs		
Example 4.	Balance to	1 kg
Demineralized water	32 g	
Carbonate of potassium glycinate	2 g	
EDTA (disodium salt)	0.5 g	
Sodium o-phenyl phenate	10 g	
Sodium bisulfite at 36° Baume	160 g	
Self-emulsified cetyl alcohol	20 g	
Quaternary ammonium compound	2 g	
Perfume	q.s.	
Precursors of oxidation dyestuffs		
Example 5.	Balance to	1 kg
Demineralized water	21 g	
Carbonate of lithium glycinate	2 g	
EDTA (disodium salt)	0.5 g	
Sodium o-phenyl phenate	10 g	
Sodium bisulfite at 36° Baume	160 g	
Self-emulsified cetyl alcohol	20 g	
Quaternary ammonium compound	2 g	
Perfume	q.s.	
Precursors of oxidation dyestuffs		
Example 6.	Balance to	1 kg
Demineralized water	44 g	
Carbonate of sodium methionate	2 g	
EDTA (disodium salt)	0.5 g	
Sodium o-phenyl phenate	10 g	
Sodium bisulfite at 36° Baume	160 g	
Self-emulsified cetyl alcohol	2 g	
Perfume	q.s.	
Precursors of oxidation dyestuffs		
Example 7.	Balance to	1 kg
Demineralized water	44 g	
Carbonate of sodium glutamate	2 g	
EDTA (disodium salt)	0.5 g	
Sodium o-phenyl phenate	10 g	
Sodium bisulfite at 36° Baume	160 g	
Self-emulsified cetyl alcohol	2 g	
Perfume	q.s.	
Precursors of oxidation dyestuffs		
Example 8.	Balance to	1 kg
Demineralized water	37 g	
Carbonate of sodium valinate	2 g	
EDTA (disodium salt)	0.5 g	
Sodium o-phenyl phenate	10 g	
Sodium bisulfite at 36° Baume	160 g	
Self-emulsified cetyl alcohol	2 g	
Perfume	q.s.	
Precursors of oxidation dyestuffs		
Example 9.	Balance to	1 kg
Demineralized water	31 kg	
Carbonate of sodium alaminate	2 g	
EDTA (disodium salt)	0.5 g	
Sodium o-phenyl phenate	10 g	
Sodium bisulfite at 36° Baume

On the other hand, the above examples do not yield sufficient results when hues lighter than the hair color are desired, or more generally lighter than the color of the support to which the dyeing composition is applied. In fact, in these specific cases and according to the well-known method the presence of oxygenated water and ammonia is attended, concurrently to the obtaining of the artificial shade, by a lighter color or clearing of the natural hair shade. This result is obtained in general by the use of high ammonia concentrations in the dyeing composition, and thus so-called "clearing" dyeing products are obtained. This is due to the alteration of the natural pigments of the hair on account of the action exerted by oxygenated water in a medium having a relatively high ammonia content.

Now, since this shading off reaction is superposed to that causing the formation of artificial pigments, it is possible to obtain hues very considerably lighter than the initial natural shade, without inasmuch producing a real bleaching action.

This technique scarcely approved by the majority of professional hair-dressers due to the strong proportions of ammonia required for its application and therefore to the resulting inconveniences already discussed hereinabove is nevertheless becoming increasingly popular on account of the relative facility with which it can be carried out, the time spared and the economy obtained for the user due to the elimination of one operation (i.e. bleaching) which is always relatively expensive.

Now, as far as hair clearing is concerned, the formulae given in the above Examples do not perform sufficiently to deserve the term of "clearing dyeing compositions". To obtain an appreciable and satisfactory clearing action the operation must be carried out at a higher pH value than that obtained with the carbonate of an amino acid alkali metal or ammonium salt, and therefore formulae containing complementary ammonia in addition to the organic bases possibly included therein, had to be developed.

In these additional formulae ammonia is present in reduced proportions ranging from 0 to 6% by weight in the form of an aqueous solution at 22° Baume in relation to the weight of the composition, not including the oxidizing agent.

It was found that the presence of the carbonate of an amino acid alkali metal or ammonium salt made it possible to obtain hair clearing results comparable to those usually obtained by using ammonia proportions corresponding to two or three times those contemplated in this invention. It is thus possible to take advantage of the attractive technique consisting in applying a color clearing composition with an ammonia proportion definitely inferior to the conventional proportions, thus reducing to a very appreciable extent the inconveniences of ammonia which are described hereinabove.

Typical formulae of clearing dyeing compositions in the form of emulsions or creams comprising limited amounts of ammonia, due to the presence of carbonate of sodium glycinate with or without an organic base such as monoethanolamine, diethanolamine, triethanolamine, morpholine and the like, will now be given in detail:

For preparing these products on a commercial scale, it is deemed more advantageous and economical to prepare the carbonate of an amino acid alkali metal of ammonium salt extemporaneously during the manufacturing process.

To this end, it is only necessary to dissolve together in demineralized water the equivalent of one molecule of alkali metal carbonate or ammonium carbonate and two molecules of amino acid. These proportions actually permit of obtaining, for example, carbonate of sodium glycinate:

In addition, this method permits of taking advantage of the relative proportions of alkali metal carbonate or ammonium carbonate in relation to the amino-acid. Thus, it is possible, by using certain formulae, to operate in the presence of an excess of alkali metal carbonate such as sodium carbonate, and, thus improve the performances in the case of moderately receptive fibres or hair.

A few examples of these formulae are given hereinafter in the form of emulsions or creams:

Example 36.

Demineralized water	Balance to	1 kg
Carbonate of sodium glycinate		28 g
Sodium carbonate		12 g
EDTA (disodium salt)		2 g
Sodium o-phenyl phenate		0.5 g
Sodium bisulfite at 36° Baume		10 g
Self-emulsified cetyl alcohol		160 g
Quaternary ammonium compound		20 g
Monooethanolamine		30 g
Ammonia at 22° Baume		60 g
Perfume		2 g
Precursors of oxidation dyestuffs		q.s.

Example 37.

Demineralized water	Balance to	1 kg
Carbonate of sodium glycinate		28 g
Sodium carbonate		12 g
EDTA (disodium salt)		2 g
Sodium o-phenyl phenate		0.5 g
Sodium bisulfite at 36° Baume		10 g
Self-emulsified cetyl alcohol		160 g
Quaternary ammonium compound		20 g
Monooethanolamine		30 g
Ammonia at 22° Baume		60 g
Perfume		2 g
Precursors of oxidation dyestuffs		q.s.

Example 38.

Demineralized water	Balance to	1 kg
Carbonate of sodium glycinate		28 g
Sodium carbonate		12 g
EDTA (disodium salt)		2 g
Sodium o-phenyl phenate		0.5 g
Sodium bisulfite at 36° Baume		10 g
Self-emulsified cetyl alcohol		160 g
Quaternary ammonium compound		20 g
Monooethanolamine		30 g
Ammonia at 22° Baume		60 g
Perfume		2 g
Precursors of oxidation dyestuffs		q.s.

Example 39.

Demineralized water	Balance to	1 kg
Carbonate of sodium glycinate		28 g
Sodium carbonate		12 g
EDTA (disodium salt)		2 g
Sodium o-phenyl phenate		0.5 g
Sodium bisulfite at 36° Baume		10 g
Self-emulsified cetyl alcohol		160 g
Quaternary ammonium compound		20 g
Ammonia at 22° Baume		60 g
Monooethanolamine		2 g
Perfume		q.s.
Precursors of oxidation dyestuffs		q.s.

Example 40.

-Continued

5	Demineralized water	Balance to	1 kg
	Carbonate of sodium glycinate		13.3 g
	Sodium carbonate		26.7 g
	EDTA (disodium salt)		2 g
	Sodium o-phenyl phenate		0.5 g
	Sodium bisulfite at 36° Baume		10 g
	Self-emulsified cetyl alcohol		160 g
	Quaternary ammonium compound		20 g
	Ammonia at 22° Baume		60 g
	Monooethanolamine		30 g
	Perfume		2 g
10	Precursors of oxidation dyestuffs	Balance to	q.s.
	Example 41.		
	Demineralized water	Balance to	1 kg
	Carbonate of sodium glycinate		13.3 g
	Sodium carbonate		26.7 g
	EDTA (disodium salt)		2 g
	Sodium o-phenyl phenate		0.5 g
	Sodium bisulfite at 36° Baume		10 g
	Self-emulsified cetyl alcohol		160 g
	Quaternary ammonium compound		20 g
	Ammonia at 22° Baume		50 g
	Monooethanolamine		20 g
	Perfume		2 g
	Precursors of oxidation dyestuffs		q.s.

What I claim is:

1. A composition for dyeing keratinic fibres and human hair comprising an aqueous mixture containing about 0.2 to 15 wt. % of an oxidation dyestuff precursor selected from the group consisting of p-phenylenediamine, p-toluylenediamine, m-toluylenediamine, nitro p-phenylenediamine, 2,4 - di-amino anisol sulfate, p-N-methylamino phenol sulfate, resorcinol, hydroquinone and mixtures thereof and about 1 to 10 wt. % of a carbonate of an alkali metal salt of an amino acid as an alkaliizer, said amino acid being selected from the group consisting of glycine, lysine, methionine, tyrosine, glutamic acid, leucine, valine and alanine, and said alkali metal being selected from the group consisting of sodium, potassium and lithium.
2. The composition of claim 1, further including about 1 to 7 wt. % of an organic base selected from the group consisting of morpholine, monoethanolamine, diethanolamine and triethanolamine.
3. The composition of claim 1, further including about 5 to 6 wt. % of ammonium hydroxide in the form of an aqueous solution at 22° Baume based on the weight of said composition.
4. The composition of claim 2, further including about 5 to 6 wt. % of ammonium hydroxide in the form of an aqueous solution at 22° Baume based on the weight of said composition.
5. The composition of claim 1, further including sodium carbonate.
6. The composition of claim 1, wherein said alkaliizer is the carbonate of sodium glycinate.
7. The composition of claim 1, wherein said alkaliizer is the carbonate of sodium glutamate.
8. The composition of claim 2, wherein said alkaliizer is the carbonate of sodium glycinate and said organic base is monoethanolamine.
9. The composition of claim 4, wherein said alkaliizer is the carbonate of sodium glycinate and said organic base is monoethanolamine.
